UNITED STATES PATENT OFFICE

109,996

DESIGN FOR A FISH KNIFE OR SIMILAR ARTICLE

Albert M. Baer, New York, N. Y.

Application November 11, 1937, Serial No. 72,809

Term of patent 7 years

To all whom it may concern:

Be it known that I, Albert M. Baer, a citizen of the United States and resident of New York, in the county and State of New York, have invented a new, original, and ornamental Design for a Fish Knife or Similar Article, of which the following is a specification, reference being had to the accompanying drawing, forming part thereof.

In the drawing:

Fig. 1 is a side view of a fish knife or similar article showing my new design.

Fig. 2 is an edge view of the fish knife or similar article shown in Fig. 1.

I claim:

The ornamental design for a fish knife or similar article substantially as shown.

ALBERT M. BAER.
